J. W. Cooksey
ATTORNEY.

UNITED STATES PATENT OFFICE.

WILLIAM P. EARNHEART, OF INDIANAPOLIS, INDIANA.

LIQUID-SERVING DEVICE.

1,131,495.

Specification of Letters Patent. Patented Mar. 9, 1915.

Application filed October 27, 1913. Serial No. 797,469.

To all whom it may concern:

Be it known that I, WILLIAM P. EARNHEART, a citizen of the United States, and a resident of Woodruff Place, Indianapolis, in the county of Marion and State of Indiana, have invented a new and useful Improvement in Liquid-Serving Devices; and I do hereby declare the following to be a full, clear, and exact description thereof.

10 My invention relates to liquid serving devices and particularly to such devices as are used on containers for serving coffee, tea, milk, cream, etc.

15 The object of my invention is to provide a cheap, simple and efficient form of liquid serving device which will be adapted to be operated by one hand and which will serve liquids in predetermined, limited or continuous quantities as desired, and which will also 20 protect the liquid from any contamination from passing over exposed parts thus rendering the same perfectly sanitary.

25 My invention consists, generally stated, in the novel arrangement, construction and combination of parts as hereinafter more specifically set forth and described and particularly pointed out in the claims.

30 To enable others skilled in the art to which my invention appertains to construct, use and operate my improved serving device I will describe the same more fully referring to the accompanying drawing in which:—

35 Figure 1 is a side elevation of my improved liquid serving device. Fig. 2 is a like view having part of the same broken away to disclose the interior of the same. Fig. 3 is a side elevation of the sliding stem used in my improved server. Fig. 4 is a front view of the lever controlling the operation 40 of the server. Fig. 5 is a side view of the same. Figs. 6 and 7 are detail views of the plate used in connection with the controlling lever. Fig. 8 is a partial vertical view of the device showing the valve in its lower- 45 most position.

Like symbols of reference herein indicate like parts in each of the figures of the drawing.

As illustrated in the drawing my improved liquid serving device is connected to a liquid container or tank R by any convenient means and consists of a body portion F which has a valve Q in the horizontal portion of the same for opening and shutting off the supply of fluid to the server. The vertical portion of the body F has a thread

on the inside of the same at its lower end for receiving a bottom portion G to form the chamber T, and such bottom portion has its lower end terminating in a tubular portion 60 or sleeve through which a tube C is adapted to act as later explained. Within the interior of the body portion F and at the top of the vertical portion thereof is a partition U which has an opening in the center of the 65 same for receiving a tube C' as later explained and such portion forms the chamber S above the same and the top of the chamber T. The tubes C and C' are connected by suitable means to a solid circular valve body 70 A which has a shoulder B around the same and the tube C is provided with suitable perforations D below such valve body while the tube C' has perforations D' directly above said valve body, the purpose of which is explained later. Between the shoulder B on the valve body A and the partition U a spiral spring E is located so that there is at 75 all times a tendency to keep the said valve body at the bottom of the chamber T. The 80 valve body A is provided with a seat X at its upper end and Y at its lower end for engaging with the seats V and W respectively in the partition U and bottom portion G.

85 The lower end of the sleeve on the bottom portion G is threaded in order to receive a metal cap H and enough space is left between the end of the sleeve and the cap to provide a stuffing box I so that there will be 90 no leakage of the liquid between the same and the tube C.

95 The bottom of the tube C is provided with cross-arm or operating bar M which is so attached to said tube as to permit the bottom of the same to have the free opening N.

100 The cap H is provided at a point in line with the operating piece M with a plate J as shown in Figs. 6 and 7 and has its top and bottom edges bent over to prevent any movement of the same while the outer face thereof is provided with a raised portion P for alternately engaging with recesses O on a lever K and said plate and lever are secured in place on the cap H by means of 105 a screw L.

110 The use and operation of my improved serving device is as follows:— The valve Q in the horizontal portion of the body F may be opened or closed as desired and when open the liquid in the tank R is permitted to fill the chamber S above the parti-

tion U while the tube C' will allow the same to flow through the perforations D' and fill the chamber T. Considering the lever K in a horizontal instead of a vertical position as shown in Figs. 1 and 2 and the valve body A resting by its seat Y in the seat W it is desired to place milk, cream or other liquid in a cup or glass in a predetermined volume. The bottom portion G is adjusted 5 in the body portion F so as to regulate the capacity of the chamber T to the amount of liquid desired in the vessel and then the vessel is placed against the cross-arm or operating bar M and pressed upward. This 10 movement will depress the spiral spring E and the seat X on the valve body A will engage with the seat V in the partition U while the liquid in the chamber T will flow through the perforations D in the tube C 15 and through the open end N of such tube into the vessel. As soon as the vessel is withdrawn from the operating bar M the spiral spring E will immediately return the tubes C and C' to their initial position. While 20 the vessel is being filled no liquid will enter the chamber T from the chamber S as the perforations D' in the tube C' will be entirely above the partition U so that the two 25 chambers will be sealed tightly against the flow of liquid from one to the other. When 30 the spring E has returned the tubes C and C' to their initial position the liquid from the chamber S will pass through the end of the tube C' and through the perforations 35 D' into the chamber T and will be prevented from leaving said latter chamber by reason of the perforations D in the tube C being below the level of the bottom of such chamber and in the sleeve of the bottom 40 portion G.

When it is desired to fill the vessel such as a cup or glass with liquid from the tank R by a continuous flow, the lever K which is in a vertical position in the drawing will 45 be pressed to such position from its horizontal position as just explained so that the center recess O in said lever will engage with the raised portion P in the plate J to hold the same in position. The cup or 50 glass is now placed against the operating bar M as described and pressed upward until the said bar strikes against the lever K at which point the parts are in a position such as shown in Fig. 2. The perforations 55 D' in the tube C' being partially above and partially below the partition U permit the fluid to flow freely from the chamber S to the chamber T while the perforations D in the tube C being above the bottom of the 60 chamber T the liquid will flow freely from said chamber and through said perforations and the end N of the tube C into the vessel.

It will thus be seen that my improved 65 serving device can be used for serving liquids in predetermined, limited or con-

tinuous quantities and the whole will be operated with one hand thus eliminating the necessity of holding the glass or cup with one hand and turning a spigot with the other. The serving device is positive and 70 complete in its action and from the standpoint of economy it is perfect as there is no drippage.

It will readily be observed that no person 75 or foreign substance comes in contact with the liquid while serving and the liquid is delivered from a tube instead of over or around a metal stem so that no flies or floating substance in the air infest that part and leave infection to be washed away with the 80 liquid at the next serving. These points insure a perfectly sanitary server.

By closing the valve Q the serving device 85 can be readily cut out of operation, disconnected and the parts cleaned or repaired 90 without emptying the tank and without the loss of any liquid.

Various modifications and changes in the design, operation and application of my improved serving device may be resorted to 95 without departing from the spirit of the invention or sacrificing any of its advantages.

What I claim as my invention and desire 95 to secure by Letters Patent is:—

1. A device for serving liquids from a container, consisting of a body portion having an upper and a lower chamber, said lower chamber adapted to be regulated in size and divided from said upper chamber by a partition, a valve member consisting of a tube for controlling the admission of fluid from the upper to the lower chamber and a tube for controlling the release of the liquid from said lower chamber, said first named tube 100 normally admitting fluid to said lower chamber and said second named tube normally preventing the escape of liquid from said lower chamber, means for raising said valve member to open said lower chamber, and 110 means for regulating the height to which said valve member may be raised in order to provide a continuous or a limited quantity of liquid.

2. A device for serving liquids from a container, consisting of a body portion having an upper and a lower chamber, said lower chamber adapted to be regulated in size and divided from said upper chamber by a partition, a valve member extending through 115 said partition and consisting of a tube for controlling the admission of fluid from the upper to the lower chamber and a tube for controlling the release of the liquid from said lower chamber, said first named tube 120 normally admitting fluid to said lower chamber and said second named tube normally preventing the escape of liquid from said lower chamber, means for raising said valve member to open said lower chamber, and 125 means for regulating the height to which said valve member may be raised in order to provide a continuous or a limited quantity of liquid.

means for regulating the height to which said valve member may be raised in order to provide a continuous or a limited quantity of liquid.

5. 3. A device for serving liquids from a container, consisting of a body portion having an upper and a lower chamber, said lower chamber adapted to be regulated in size and divided from said upper chamber by a partition, a valve member consisting of a perforated tube for controlling the admission of fluid from the upper to the lower chamber and a tube for controlling the release of the liquid from said lower chamber, said 10 first named tube normally admitting fluid to said lower chamber and said second named tube normally preventing the escape of liquid from said lower chamber, means for raising said valve member to open said lower chamber, and means for regulating the height to which said valve member may be raised in order to provide a continuous or a limited quantity of liquid.
4. A device for serving liquids from a container, consisting of a body portion having an upper and a lower chamber, said lower chamber adapted to be regulated in size and divided from said upper chamber by a partition, a valve member extending through 25 said partition and consisting of a perforated tube for controlling the admission of fluid from the upper to the lower chamber and a tube for controlling the release of the liquid from said lower chamber, said first named
- tube normally admitting fluid to said lower 35 chamber and said second named tube normally preventing the escape of liquid from said lower chamber, means for raising said valve member to open said lower chamber, and means for regulating the height to which said valve member may be raised in order to provide a continuous or a limited quantity of liquid.
5. A device for serving liquids from a container, consisting of a body portion having an upper and a lower chamber, said lower chamber adapted to be regulated in size and divided from said upper chamber by a partition, a valve member consisting of a tube 40 for controlling the admission of fluid from the upper to the lower chamber and a tube for controlling the release of the liquid from said lower chamber, said first named tube normally admitting fluid to said lower chamber and said second named tube normally preventing the escape of liquid from said lower chamber, means for raising said valve member to open said lower chamber, and a lever arm engaging said means for regulating the height to which said valve member 45 may be raised in order to provide a continuous or a limited quantity of liquid.

In testimony whereof, I the said WILLIAM P. EARNHEART have hereunto set my hand.

WILLIAM P. EARNHEART.
